UNITED STATES PATENT OFFICE.

CHRISTIAN J. WEINMAN, OF DAYTON, OHIO.

DESIGN FOR A FRAME FOR HACKSAWS.

SPECIFICATION forming part of Design No. 33,422, dated October 28, 1900.

Application filed September 14, 1900. Serial No. 30,074. Term of patent 7 years.

To all whom it may concern:

Be it known that I, CHRISTIAN J. WEINMAN, a citizen of the United States, residing at Dayton, in the county of Montgomery and State of Ohio, have invented a certain new and useful Design for a Frame for Hacksaws; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a side elevation showing my new design. Fig. 2 is an end elevation. Fig. 3 is a vertical sectional elevation on the line $x-x$ of Fig. 1.

As shown in the drawings, the leading or material feature of my design consists of a frame having a sunken wall A or a wall which is surrounded by flanges B on its two vertical ends and a curved flange C on the bottom, the said flanges projecting equal distances from the wall on both sides. The lower portions D D', with flanges D' D'', form the feet of the frame. The said wall on one side of the vertical center has an oblong opening E, which

is likewise surrounded by a flange E'. On the other side of the vertical center of said wall, adjacent to the top thereof, is a circular sunken panel F, having an opening F' in the center thereof. One end of the frame has a bracket G projected therefrom, upon the outer end of which there is a projection H. The top of the frame has a dovetail projection I thereon with a central longitudinal opening J. The said dovetail projection extends inwardly from the end opposite that at which the bracket is located and terminates at a point beyond the vertical center of the wall A, leaving a space K between said dovetail projection and the upper or horizontal portion of the bracket.

Having described my invention, what I claim, and desire to secure by Letters Patent, is--

The design for a frame for a hacksaw as herein shown and described.

In testimony whereof I affix my signature in presence of two witnesses.

CHRISTIAN J. WEINMAN.

Witnesses:

R. J. McCARTY,
C. THEOBALD.
